(57) **CLAIM**

We claim the ornamental design for a bag caddy, as shown and described.

DESCRIPTION

FIG. 1 is a perspective view of a bag caddy embodying the invention.

FIG. 2 is a front view of the bag caddy of FIG. 1.

FIG. 3 is a rear view of the bag caddy of FIG. 1.

FIG. 4 is a first side view of the bag caddy of FIG. 1.

FIG. 5 is a second side view of the bag caddy of FIG. 1.

FIG. 6 is a top view of the bag caddy of FIG. 1; and,

FIG. 7 is a bottom view of the bag caddy of FIG. 1.

The broken lines in the figures show portions of the bag caddy that form no part of the claimed design.
